[57] CLAIM

The ornamental design for a combined bottle and cap, as shown and described.

DESCRIPTION

FIG. 1 is a top, rear perspective view of my new design for a combined bottle and cap;

FIG. 2 is a top plan view of my new design;

FIG. 3 is a bottom plan view thereof;

FIG. 4 is a right side elevation view, the left side elevation being a mirror image thereof;

FIG. 5 is a front elevation view thereof; and,

FIG. 6 is a rear elevation view thereof.
